UNITED STATES PATENT OFFICE.

HUGO F. AMMERMANN AND WILHELM LOHSE, OF NEW YORK, N. Y.

GOVERNOR.

No. 869,041.

Specification of Letters Patent.

Patented Oct. 22, 1907.

Application filed March 8, 1907. Serial No. 361,212.

To all whom it may concern:

Be it known that we, HUGO F. AMMERMANN and WILHELM LOHSE, subjects of the German Emperor, and residents of the city of New York, borough of Brooklyn, 5 in the county of Kings and State of New York, have invented a new and Improved Steam-Engine Governor, of which the following is a full, clear, and exact description.

This invention relates to steam engine governors, and 10 the object of the invention is to produce a combination throttle and governor valve, the construction of the governor valve comprising a spring; and a further object of the invention is to provide improved means for regulating the tension of this spring.

15 The invention consists in the construction and combination of parts to be more fully described hereinafter and particularly set forth in the claims.

Reference is to be had to the accompanying drawings forming a part of this specification, in which similar 20 characters of reference indicate corresponding parts in all the figures.

Figure 1 is substantially a plan of the device, the upper portion thereof being shown in cross section, together with certain other parts near the middle of the 25 view; this view may be considered as a section on the line 1—1 of Fig. 2; Fig. 2 is substantially a longitudinal vertical section, certain parts being shown in elevation; Fig. 3 is a cross section, the upper portion of this view being shown in elevation; and Fig. 4 is a detail of parts 30 of the governor.

Referring more particularly to the parts, 1 represents a globe valve, the lower portion of which is formed with a flange 2 adapted to be bolted to a pipe connection or directly to a steam chest. At the side a similar flange 35 3 is provided through which the steam enters the valve. Through the flange 3 there is an inlet opening 4, in the inner extremity of which a valve seat 5 is provided for a throttle valve 6, said throttle valve being carried upon the extremity of a threaded stem 7. This stem is 40 mounted in a guide or bonnet 8 which is screwed into the globe valve 1 opposite the inlet opening 4, and the interior of the globe valve is formed with a closed chamber or inner globe 9 into which the steam is admitted when the hand-wheel 10 is rotated in the proper direction to open the throttle valve.

45 In the wall of the inner chamber or globe 9, on the upper side, an opening 11 is provided, of circular form, and above and around this opening the valve body 1 is formed into a flange 12. Upon this flange 12 there is seated a disk 13, the middle central portion of which is formed into a downwardly projecting valve body 14. The lower extremity of this valve body 14 is received in the opening 11, whereby a tight fit of the parts is formed. The interior of the valve body 14 is formed 50 with a conical bore 15 in which there is received a low conical plug 16, the lower extremity whereof is open

as shown, so as to admit steam into the interior of the plug from the inner chamber 9. The space surrounding the valve body 14 is in communication with the outlet opening 17 from the flange 2 and the interior of the 60 globe body 1.

In the wall of the valve body 14 a plurality of slots or ports 18 are formed, and similar ports 19 are formed in the plug 16, which are adapted to register with the ports 18. On the upper face of the disk 13, an upwardly projecting stud 20, of relatively large diameter, is formed, and this stud passes through an opening formed in the flange 21 of a governor bracket 22. In this way the flange 21 seats upon the disk 13 in such a way that the parts may be connected together by 70 through bolts or studs 23, as indicated in Fig. 1. The disk 13 is provided with a central opening through which a valve stem 24 passes upwardly; the lower extremity of the said stem being rigidly attached in the head or upper end of the plug 16. This stem 24 projects above the upper surface of the stud 20 and the flange 21, and has rigidly attached thereto a radially projecting arm 25. The plug 16 is held upon its seat by means of a leaf spring 26 formed with a hub 27 which presses against the under side of the arm 25 at the stem, 75 as shown. This spring 26 is formed with oppositely projecting legs which incline slightly in a downward direction, the extremities of the legs resting upon the upper face of the flange 21, as shown. It should be understood that the spring 26 in no way prevents the 80 rotation of the stem 24.

We shall now describe the governor mechanism for controlling the governor valve 14. On one side, the bracket 22 is formed into an elongated bearing 28, as indicated most clearly in Fig. 2, and in axial alignment. 90 with this bearing, on the opposite side, the bracket is formed into a guide sleeve 29. This guide sleeve 29 and the bearing 28 are connected integrally by a yoke 30, as shown. Slidably mounted in the bearing 28 we provide a governor spindle 31. In the guide-sleeve 29 there is a thrust-head 34 formed into a shoulder 32 to receive the thrust of the spring 33, the said spring being of helical form and disposed about the reduced portion of the head, as indicated. The outer surface of the sleeve 29 is threaded for the attachment of an adjusting wheel 35, said wheel being formed near its outer end with a shoulder 36 against which the opposite end of the spring 33 thrusts. Beyond this shoulder 36 a bore 37 is formed in the wheel, of reduced diameter, and in this bore the extremity of the thrust-head 34 is 100 slidably mounted.

Within the bearing 28 a tubular sleeve 38 is provided, and the inner extremity of this sleeve projects beyond the inner end of the bearing, and is provided with a rigid collar 40 which holds the sleeve in position. 110 The outer extremity of the sleeve projects beyond the outer end of the bearing, and is threaded to receive a

governor hub 41. In this hub 41 arms 42 are pivotally mounted between transverse webs 43, and these arms are provided with weights or balls 44, which are adapted to fly out when the governor head is rotated. As indicated, these arms 42 pass through slots 45 formed in the hub 41. The inner extremities of the arms 42 are formed into toes 46 which project over and press against the end of the spindle 31, as indicated in Fig. 2. Upon the hub 41 a belt pulley 47 is attached, which is adapted to receive a belt from a suitable part of the engine, so that the governor will be rotated continuously when the engine is in operation.

The end of the spindle 31 at the pulley is formed into a square head 31^a disposed between the webs 43, as indicated in Fig. 4. From this arrangement, when the pulley is rotated the spindle 31 will also rotate. The inner end of the thrust head 34 is formed with a reduced tip 34^a and this tip extends into the bore in the hub of an arm 49, the arm being rigidly attached thereto by a set screw 34^b, as indicated. On the inner end of the spindle 31 a reduced neck 48 is formed, which is loosely mounted in the opposite end of the bore of the hub, so that its end abuts against the end of the thrust head. In this way the hub of the arm 49 forms a socket for the tail end of the governor spindle.

Near its outer end the arm 49 is provided with a pin 50 which extends through a slot 51 formed in the end of the arm 25 aforesaid. From this arrangement it should be understood that when the pulley 47 is rotated, the balls 44 will tend to fly outwardly by centrifugal force, and the toes 46 will operate to shift the spindle 31 toward the left, tending to compress the spring 33. On account of the shifting movements of the arm 49, which will result as a consequence of the shifting or sliding movement of the spindle, the arm 25 will be rotated in such a way as to rotate the stem 24. In this way the plug 16 is rotated so as to close, more or less, the amount of opening through the ports 18 and 19. In this way the valve 14 will act as a governor valve, the amount of opening through which will depend upon the speed of the engine.

We provide means for adjusting the amount of tension upon the spring. For this purpose, the thrust-head 34 is made of tubular form, the outer end being closed by a plug 52. Through this plug there is slidably mounted an indicator stem 53, the outer end whereof is rotatably mounted at 54 in an opening formed in the end of the wheel 35. Just within the plug 52 this indicator stem 53 is offset laterally and passes through an opening 55 in the forward end of the sleeve. Beyond this point it is offset laterally and downwardly so as to form a shank 56 which passes into the interior of an indicator 57, said indicator being mounted on the upper face of the flange 21, as shown. Within the indicator, the shank 56 is pivotally attached to a segment 58, which segment, through the medium of a gear train 59, operates to rotate a needle 60. The

indicator 57 is provided with a dial 61 with which the needle cooperates. The arrangement is such that when the hand-wheel 35 is unscrewed sufficiently to relieve the spring 33 of any strain, the needle 60 will then register zero on the dial. As the hand-wheel is screwed up, however, the needle will indicate at all times the amount of compression to which the spring is subjected. It should be understood that in practice, the compression to which the spring will be subjected will depend upon the number of revolutions at which the engine is to run. At slow speeds, of course, the tension on the spring will be smaller than at high speeds.

It will be observed that the disk 13 constitutes a cover for the valve body.

Having thus described our invention, we claim as new and desire to secure by Letters Patent:

1. In a governor, in combination, a governor spindle, means for shifting said spindle longitudinally controlled by the speed of the engine, a spring adapted to be compressed by the shifting of said spindle, a hand wheel for adjusting the tension of said spring, an indicator, and means connecting said hand wheel with said indicator for showing the tension on said spring. 75

2. In a governor, in combination, a guide sleeve, a thrust-head in said sleeve adapted to be shifted longitudinally, means for controlling the longitudinal shifting of said head from the engine, a bracket supporting the said head, an indicator supported on said bracket, an adjusting wheel mounted on said guide sleeve, a spring tending to shift said head and adapted to be adjusted by said adjusting wheel, and a connection from said adjusting wheel to said indicator for indicating the tension on said spring. 80

3. In a governor, in combination, a bracket, a spindle rotatably mounted therein and adapted to shift longitudinally, means for controlling the longitudinal shifting of said spindle with the speed of the engine, a tubular thrust-head mounted in said bracket and abutting said spindle, a spring disposed about said thrust-head within said sleeve and tending to force said spindle longitudinally, an adjusting wheel mounted on said sleeve and adapted to adjust the tension of said spring, an indicator mounted on said bracket, an indicator-stem mounted in said wheel and connected with said indicator whereby the tension of said spring may be shown on said indicator. 90

4. In a governor, in combination, a bracket, a governor spindle rotatably mounted and slidably mounted in said bracket, means for controlling the longitudinal shifting of said spindle by the speed of the engine, said bracket having a guide sleeve, a thrust-head abutting said spindle, a spring tending to force said spindle longitudinally, an adjusting wheel mounted on said sleeve and adapted to adjust the tension of said spring, an indicator, an indicator-stem loosely mounted in said hand-wheel, said thrust-head having a tubular body through which said stem passes, and a connection between said indicator-stem and said indicator whereby said indicator may show the tension of said spring. 105

In testimony whereof we have signed our names to this specification in the presence of two subscribing witnesses.
